UNITED STATES PATENT OFFICE.

ELZEAR MICHAUD, OF MONTREAL, QUEBEC, CANADA.

HEAD AND BACK REST FOR BEDS.

No. 831,517.

Specification of Letters Patent.

Patented Sept. 18, 1906.

Application filed September 25, 1905. Serial No. 280,098.

To all whom it may concern:

Be it known that I, ELZEAR MICHAUD, a subject of the King of Great Britain, residing at and whose post-office address is Montreal, 5 district of Montreal, Province of Quebec, Dominion of Canada, have invented certain new and useful Improvements in Head and Back Rests for Beds; and I do hereby declare that the following is a full, clear, and exact description of the invention, such as will enable others skilled in the art to which it appertains to make and use the same.

This invention relates to new and useful improvements in head and back rests adapted to be applied to beds, the object of this invention being to provide a self-contained device for that purpose which may be assembled for use and readily applied to wood and metal beds without boring or otherwise marking such beds. To that end the operative parts are all connected with rail-plates which are adapted to rest upon the bed-rails and may be removed therefrom with ease.

In the accompanying drawings is illustrated the preferred form of the device, and it will be evident that said device may be changed in form and in the various proportions without departing from this invention.

Figure 1 is a perspective view of one end of 30 a bed equipped with the invention. Fig. 2 is a fragmentary view illustrating one rail with a rail-plate thereon, to which is connected one part of the head and back rest. Fig. 3 is a detached perspective view illustrating one 35 of the rail-plates. Fig. 4 is a section on line 44 of Fig. 3, and Fig. 5 is an edge view of one of the rocker-arms of the device.

Referring to the parts, 1 represents bed-rails, upon which rest the rail-plates 2, which 40 are provided, respectively, with the depending flanges 3, 4, and 5 and with the upwardly-projecting serrated segmental flange 6 and also, if desired, with the intermediate depending locking-flange 7, which is adapted to 45 bend under a flange 1^a of a metallic bed-frame when the device is used on a metal bed.

Projecting through the flanges 4 are pivots 8, upon which are rockably supported the rocker-arms 9, which arms 9 are provided at 50 their lower portions with the inwardly and downwardly bent portions 10, at the lower extremity of which are the pins 11. Said pivots are preferably in the form of bolts which pass under the bed-rails, spanning 55 the space between contiguous flanges and

serving as locking means to hold the plates against vertical displacement, though permitting the said plates to slide longitudinally of the side rails of the bed upon which the attachment is placed. The arms 9 are provided with the inwardly-projecting perforated lugs 12, through which pass the spring-actuated rod 13, the lower end of which is serrated to correspond with and engage the serrations 14 of the segment 6. A spring 15 surrounds the rods 13 and bears against the thickened portion 16 to force said rods downwardly, so that the serrated head portion 17 of said rod will engage with the serrations 14. The upper portions 18 of the rocker-arms 9 are recessed, and in said recesses are placed the lower end of the frame 19. The recessed portion 18 may be screw-threaded for engagement with said frame. Secured by the clips 20 are levers 21, which engage the rods 13 70 and by means of which the head portion 17 of said rods 13 may be lifted to release said head portion from engagement with the segment 6. Connected with the perforated flanges 5 are springs 22, to the opposite end 80 of which are connected adjusting-links 23, which links are provided with a series of notches 24, which notches are adapted to engage the pins 11 to connect said springs 22 with the depending portions 10 of the rocker-arms 9, and it will be evident that the tension of the springs 22 may be readily adjusted 85 by means of the take-up links 23. Extending longitudinally of the plate 2 is a rib 2^a, which serves as a reinforce for said rib. 90

Owing to the fact that the rocker-arms and the springs are both connected to depending flanges of the plates 2, it is evident that the device herein illustrated is a self-contained head and back rest which may be readily applied to bed-rails whether said rails are of wood or metal, and when used with metal rails the depending flanges 7 may be bent inwardly, as shown in Figs. 3 and 4, to prevent springing of the plates 2 under stress of the 100 springs during operation of the device. As this device is intended for use especially in hospitals the manipulating-levers 21 are carried to the upper extremity of the frame 19, so as to be out of reach of the patient occupying the bed under normal conditions. 105

What I claim is—

1. In a detachable head and back rest, rail-plates having depending flanges, a serrated locking-segment, integral with one of said 110

rail-plates, a pivotally-supported frame and locking means carried by said frame.

2. In a detachable head and back rest, rail-plates having integral depending flanges, 5 springs connected with some of said flanges, a pivotally-supported frame, depending extensions on said frame, coöperating with said springs and means for locking said frame in different positions.

10 3. In a detachable head and back rest, rail-plates having integral depending flanges, springs connected with some of said flanges, a pivotally-supported frame, a perforated lug on said frame, integral extensions on said 15 frame, means connecting said extensions with said springs, a locking-plate, and a locking-rod projecting through said perforated lugs, said rod being adapted to engage with said plate.

20 4. In a bed attachment for supporting a head and back rest, rail members having integral depending flanges, springs connected with some of said flanges, a rockable supporting member pivotally mounted on said 25 rail members, and an extension on said supporting member connected with said springs.

25 5. In a detachable head and back rest, rail-plates, springs connected at one end with said plates, a frame pivotally supported by 30 said plates, extensions on said frame projecting below the pivots thereof, means for connecting the springs with said extensions and means for locking said frame in a plurality of positions.

35 6. In a detachable head and back rest, rail-plates having integral depending flanges, springs connected with some of said flanges, recessed adjusting-links connected with said springs, a frame pivotally connected with 40 said plates, locking means carried by said frame, and extensions on said frame with which said links are adapted to engage.

45 7. In a detachable head and back rest, a pair of rail-plates, flanges depending from said plates, a serrated segment integral with one plate, a frame pivotally supported by said flanges, a perforated lug on said frame, a reciprocating rod guided by said lug, and a locking-pawl on said rod, in combination 50 with extensions on said frame extending below the pivots thereof and springs connected with said extensions at one end and with flanges near the opposite end of said plate at their opposite ends.

55 8. In a detachable head and back rest for beds, slidable rail-plates, integral flanges on said plates, springs connected with said plates, a rockable supporting-frame having depending extensions and means connecting 60 said extensions with said springs.

9. In a detachable head and back rest for beds, flanged rail-plates adapted to rest upon the side rails of a bed, a rockable supporting-frame pivotally mounted upon flanges of said 65 rail-plates, springs connected with said rock-

able frame below the pivots thereof and also with said side plates, and means for locking said rockable frame in different positions.

10. In a detachable head and back rest for beds, flanged rail-plates adapted to rest upon 70 the side rails of a bed, a rockable supporting-frame pivotally mounted upon flanges of said rail-plates, springs connected with said rockable frame below the pivots thereof and also with said side plates, and means for adjusting 75 the tension of said springs.

11. In a detachable back and head rest for beds, rail-plates having integral depending flanges adapted to span the side rails of a bed, 80 springs connected with some of said flanges, a pivotally-supported frame carried by said flanges, depending extensions on said frame, coöperating with said springs and means for adjusting the tension of said springs.

12. In a detachable head and back rest 85 adapted to be placed upon the side rails of a bed, rail-plates having integral flanges projecting at an angle, to said plates, springs connected with some of said flanges, a rockable frame mounted on some of said flanges, 90 locking means adapted to secure said frame in different positions and means for connecting said frame with said springs.

13. In a detachable head and back rest for beds adapted to be mounted on the side rails 95 of said beds, the combination comprising a rockable frame, slidable rail-plates on which said frame is pivotally mounted, means for locking said frame in different positions, springs connected with said rail-plates and 100 with said frame and means for locking said rail-plates against vertical displacement on said side rails.

14. In an attachment adapted to be secured upon the side rails of a bed, slidable 105 rail-plates, means for locking said plates, against vertical movement but permitting them to slide longitudinally of the side rails of the bed, a rockable frame carried by said rail-plates, springs connecting said frame 110 with said rail-plates and means for locking said frame in different positions.

15. In a detachable head and back rest adapted to be secured upon the side rails of a bed; the combination comprising flanged 115 rail-plates, springs connected with some of the flanges of said rail-plates, a rockable frame mounted on said plates, means for locking said frame in different positions, and means for connecting said springs with said 120 frame.

16. In a detachable head and back rest for beds adapted to be mounted upon the side rails of a bed, the combination comprising flanged and slidable rail-plates, springs connected with some of the flanges of said plates, a rockable frame mounted upon said rail-plates, a spring-actuated reciprocating locking member coöperating with serrations on 125 one of the flanges of one of the rail-plates and 130

means connecting said springs with said frame.

17. In a detachable head and back rest adapted to be slidably mounted upon the 5 side rails of a bed, slidable rail-plates having integral flanges, a rockable frame mounted on said rail-plates means for locking said frame in different positions, depending extensions on said frame, springs connected 10 with flanges on said rail-plates and means connecting said springs with said depending extensions of the frame.

18. In a detachable head and back rest adapted to be mounted upon the side rails of

a bed, flanged rail-plates adapted to rest on 15 said side rails, means for locking said plates against vertical displacement, a rockable back and head rest frame having depending extensions, springs connected with said extensions and with flanges of said rail-plates, 20 and means for locking said frame in different positions.

In testimony whereof I have signed my name in the presence of two witnesses.

ELZEAR MICHAUD.
